UNITED STATES PATENT OFFICE.

CLYDE B. WHITMORE, OF GALENA, ILLINOIS.

TRAFFIC GUIDE BUTTON.

Application filed August 16, 1926. Serial No. 129,544.

My invention relates to improvements in traffic guide buttons, and it consists in the combinations, constructions, and arrangements herein described and claimed. It is a well known fact that aluminum retains its luster, when placed outdoors, irrespective of the weather conditions. However, we find that in constructing traffic guide buttons of soft aluminum, they will not withstand heavy traffic, and by constructing traffic guide buttons of hard aluminum, they are somewhat brittle and break at the neck which extends into the street.

An object of my invention is to provide a traffic guide button which is durable in construction, and which provides a brilliant surface.

A further object of my invention is to provide a device of the type described which may be readily applied to a street irrespective of the material of which the street is constructed.

A further object of my invention is to provide a device of the type described which is inexpensive to manufacture.

A further object of my invention is to provide a device of the type described by means of which words, such as "Stop" and various other traffic indications may be formed by the use of a plurality of buttons.

Other objects and advantages will appear in the following specification, and the novel features of the invention will be particularly pointed out in the appended claims.

My invention is illustrated in the accompanying drawings, forming part of this application, in which—

Figure 1 is a plan view of the buttons as applied to a street to form the word "Stop,"

Figure 2 is a plan view of a plurality of buttons as forming a traffic guide,

Figure 3 is a side elevation of the device as being applied to a street.

Figure 4 is a sectional view of the device when secured in place, and

Figure 5 is a bottom plan view of the device.

In carrying out my invention, I provide a head portion 1 and an integral neck 2 which are constructed of a very durable material, such as malleable iron. The head portion 1 is provided with a flat surface 3 and a rounded surface 4. An annular bead 5 is integral with the head portion 1 and is

disposed adjacent the peripheral edge of the head portion. An aluminum plate 6 is disposed upon the head 1, the outer edge of the plate being bent downwardly and inwardly and crimped over the bead 5, as clearly shown in Figure 4.

The neck 2 is provided with a core 7, the walls thereof extending outwardly to the lower end of the neck and to a point substantially adjacent the outer wall of the neck. The neck 2 is further provided with cutaway portions forming prongs 8 which come to points at the lower end of the neck 2.

In applying the device to a street, holes are first bored for receiving the greater part of the neck 2. When the neck is placed within the hole, the head portion 2 is a slight distance above the surface of the street, see Figure 3. The head and neck are then forced downwardly by any suitable means until the surface 3 is adjacent to the surface of the street. During this movement, the prongs 8 are forced outwardly, thus rigidly securing the head 1 and the neck 2 in place. The tapering inner surfaces of the prongs cause the prongs to bend outwardly instead of inwardly.

I claim:

1. A device of the type described comprising a head portion having an annular bead adjacent the peripheral edge thereof, a plate disposed upon said head portion, the outer portion of said plate being bent inwardly around said bead, said plate maintaining a brilliant surface irrespective of the wear thereon, and means for securing said head portion and said plate adjacent to the surface of a street.

2. A device of the type described comprising a head portion having an annular bead adjacent the peripheral edge thereof, a plate disposed upon said head portion, the outer portion of said plate being bent inwardly around said bead, said plate maintaining a brilliant surface irrespective of the wear thereon, means for securing said head portion and said plate adjacent to the surface of a street, said means comprising a neck integral with said head portion, and prongs integral with said neck and being adapted to extend outwardly when said head and said neck are moved downwardly.

CLYDE B. WHITMORE.
